UNITED STATES PATENT OFFICE.

ROBERT F. LONABERGER AND CALVIN R. BALMER, OF READING, PENNSYLVANIA,
ASSIGNORS OF ONE-THIRD TO JACOB W. EASTERLINE, OF READING, PENNSYLVANIA.

TWO-CYCLE GAS-ENGINE.

1,208,805.

Specification of Letters Patent. Patented Dec. 19, 1916.

Application filed April 6, 1915. Serial No. 19,436.

To all whom it may concern:

Be it known that we, ROBERT F. LONABERGER and CALVIN R. BALMER, both citizens of the United States, residing at Reading, in the county of Berks and State of Pennsylvania, have invented certain new and useful Improvements in Two-Cycle Gas-Engines, of which the following is a specification.

Our invention relates to two-cycle internal combustion engines, and particularly to that type in which axially aligned working and pump cylinders are employed; and it consists mainly in improved mechanism for advantageously controlling the inflowing and discharging gases, as hereinafter fully described in connection with the accompanying drawings, the novel features being pointed out in the claims.

Figure 1 is a central vertical section through one of the working-and-pump cylinders, being on the line 1—1 of Fig. 2. Fig. 2 is a sectional plan view, taken on the line 2—2 of Fig. 1. Fig. 3 is a cross-sectional view of the intake-valve and its cage, taken on the line 3—3 of Fig. 2; and Figs. 4 and 5 are similar views of the bypass-valve and its cage, taken on the lines 4—4 and 5—5 respectively of Fig. 2. Figs. 6 and 7 are separate views of the rotary bypass and intake valves respectively; each being shown in central longitudinal section.

A represents the main engine shaft, suitably mounted in a crank casing B, upon which is secured a pair of working-and-pump cylinders, marked C and C' respectively; the parallel axes of the cylinders being perpendicular to the shaft A. As shown each of this pair of cylinders, C, C', is of the well known type comprising a working portion 5 and an enlarged coaxial pump portion 6; with a working piston 7 in the cylinder 5, extending into the pump cylinder 6 and having an enlargement therein forming a pumping-piston 8 for the annular pumping chamber 9. One of these working-and-pump pistons of cylinder C is shown in fully lowered position with its piston rod 10 connected to a crank pin 11 of the shaft A, while the other is indicated, by dotted lines, in its fully raised position in the other cylinder C'.

Our invention consists primarily in improved mechanism for advantageously controlling the supply of gas from the carbureter to the respective cylinders, and the

proper discharge of the products of combustion therefrom, as embodied in preferred form in the drawings, as hereinafter specifically described; the construction shown providing also for jointly water-jacketing the working cylinders and the gas-control mechanism so as to advantageously preheat the charges supplied to the working cylinders. This gas-control mechanism, as shown, comprises separate intake and bypass valve housings or cages, marked D and E respectively. One of these cages, D, is provided with a carbureter connection 15, and serves, with its valve, to control the supply of gas to the annular pumping chambers 9, 9 of the respective pumping cylinders; while the other, E, receives the initially compressed gas from said pumping cylinder and controls its supply to the respective working cylinders. These cages are shown as cylindrical in form, each being adapted for the reception of a hollow rotary valve, F and G respectively; and they extend along the line of junction of the working and pump portions of said cylinders, on opposite sides thereof as indicated, so as to permit of conveniently providing communication between each valve cage and the respective cylinders.

The intake-valve cage D is provided near each end thereof with a port 20 or 20^a, leading through port 20^b or 20^c into the adjacent annular pumping chamber 9, and these cage ports are opened and closed at proper times by the hollow rotary intake valve F, which receives the flow from the carbureter through openings 22 and is provided with a registering port or ports 21, 21^a at each end. As illustrated there are two oppositely arranged ports 21 or 21^a at each end of the valve F, the speed of rotation of the valve being reduced relative to the engine shaft A from which it is driven, so as to deliver to each pumping chamber at each half-rotation of the valve. This slowing up of the valve F permits the intake ports to be advantageously held open during the descent of the pumping piston 8.

The bypass-valve cage E, and its hollow rotary valve G, are similar in general form and arrangement to the intake-cage D and its valve F; but they are adopted to bypass the initially compressed gas from the pump chamber of each cylinder into the working chamber of the other cylinder, through the hollow valve G which serves as a temporary

reservoir for each passing charge. The ports 25, 26 from one pumping chamber 9, permit passage of gas therefrom into the hollow valve G when the port 27 of the latter, is 5 turned into register therewith; and this gas is passed from the valve chamber into the lower end of the working chamber of the other cylinder, through ports 28^a, 29^a, when the valve port 30^a is turned into register 10 with the latter, as further referred to hereinafter. Each working cylinder 5 is provided with a top exhaust passage 35, the opening and closing of which are definitely timed by a valve 36, which is positively operated in unison with the piston movements, 15 through the medium of a cam-carrying shaft 37 as indicated.

The working portion of each cylinder, as shown, is provided with an encircling water-jacket 40 as usual. In order to utilize the heat imparted to the water by contact with these working cylinders, we also form each valve housing or cage with its own water jacket, 41 or 41^a, surrounding the cylindrical 25 valve-containing portion thereof; and we arrange these cage jackets in communication with the cylinder jackets 40, as indicated at 42, 43, so that the water is circulated around the housings of the hollow rotary valves in 30 which the charging gas is temporarily contained.

As shown in Fig. 1 the near working-and-pump piston 7—8 has been moved to its lowest position in the working-and-pump 35 cylinder C. The pump piston 8 has drawn a full charge of gas into the annular pumping chamber 9; through the connection 15 from the carbureter; into the hollow-valve F through openings 20; and through one of 40 the valve ports 21 and the cylinder port 20^b, into the chamber 9, the port 21 being now closed (Fig. 1). This indrawn gas, somewhat heated during its passage through the water-jacketed intake-valve F and its housing 45 D, is compressed by the rising of the piston 8 in the annular chamber 9, and is admitted into the central chamber of the rotary bypass-valve G through the fixed ports 25, 26 and the valve port 27; the valve being turned so that said port will register 50 with ports 25, 26 only after a partial rising movement of the piston (approximately 47° of rotation of the crank shaft) to initially compress the charge contained therein. 55 This valve port 27 in passing the fixed port 26, which latter partially extends around the valve G as shown provides a considerable time (approximately 133° of rotation of the crank shaft) for the charge to pass into the 60 central chamber of the valve G. While the piston in cylinder C is moving upward and filling the chamber of valve G with a charge as described, the raised piston in cylinder C' (indicated by dotted lines in Fig. 1) is 65 moving downward correspondingly so as to

be ready for the delivery of this charge above it through valve port 30^a and fixed ports 28^a, 29^a. The port 30^a does not open until the inlet port 27 from the cylinder C has passed over the greater part of its fixed port 26 (approximately 86° of rotation of the crank shaft), this movement allowing time to compress and store up the charge in the chamber of valve G. The port 30^a then opens to the working chamber 5 of cylinder 70 C' through fixed ports 28^a, 29^a, while inlet port 27 is closing, the two being open together only until the port 30^a is in full register with port 28^a (approximately 47° of rotation of the shaft). The port 30^a remains 75 open for a time, after the closing of the inlet valve port 27 (approximately 47° of rotation of the crank shaft), thus giving time to transfer the entire compressed charge from the valve G to the chamber 5 of the 80 cylinder C'. Upon the closing of the port 30^a the inlet port 27^a opens through ports 25^a, 26^a, admitting the charge of gas to the interior of valve G from the pump chamber 9 of cylinder C' the piston in the latter 85 having partly risen to initially compress the charge. The valve G then compresses, stores and discharges this charge, through valve port 30, and fixed ports 28, 29 to the working chamber 5 of cylinder C in the 90 manner just described for the compressing, 95 storing and discharging of the charge of gas into the working portion 5 of cylinder C'. The valve G is rotated at crank shaft speed and for each revolution, receives, stores and 100 discharges a measured charge of gas to each working cylinder. As the fresh charge enters from the bypass valve, the products of the preceding combustion are permitted to escape through the top exhaust passage 105 35, the valve 36 being positively held open, by proper adjustment of its operating means, until the burnt gases have been forced out by the heavier new gas, thus insuring maximum 110 efficiency. The circulation of the cooling 115 medium which surrounds the working cylinders, around both the intake and bypass valves also, serves to satisfactorily preheat the new gas during its passage to the working cylinders. The positive control of the 115 inflow of gas into the working cylinders by the bypass valve, independently of the piston movement past the inlet port 29, prevents harmful action and leakage incident to dependence upon the piston for cut off. The 120 separate intake and bypass valves, and the properly timed coöperating exhaust valve, permit of securing most advantageous full control and effective results.

The preferred construction described may 125 obviously be modified without departing from the invention.

What we claim is:

1. In a two-cycle internal combustion engine, a pair of working-and-pump cylinders 130

- having intake-valve and bypass-valve housings arranged on opposite sides of the cylinders and each provided with independent ports and passageways to the respective 5 pump cylinders and the bypass-valve housing provided also with separate ports and passageways to the respective working cylinders, and valves in said housings arranged to coöperatively control the several ports.
- 10 2. In a two-cycle internal combustion engine, a pair of working-and-pump cylinders having separate intake-valve and bypass-valve housings oppositely arranged in line with the junctions of the working and pump 15 portions of said cylinders and each provided with separate ports to the respective pump cylinders and the bypass-valve housing provided also with separate ports to the respective working cylinders, and valves in said 20 housings arranged to coöperatively control the several ports.
3. In a two-cycle internal combustion engine, a pair of working-and-pump cylinders having separate cylindrical intake-valve and 25 bypass-valve housings arranged on opposite sides of the cylinders and each provided with separate ports to the respective pump cylinders and the bypass-valve housing provided also with separate ports to the respective 30 working cylinders, and cylindrical rotary valves in said housings each having a central chamber with openings therefrom arranged to register with the several ports.
4. In a two-cycle internal combustion engine, a pair of working-and-pump cylinders having separate cylindrical intake-valve and bypass-valve housings arranged on opposite sides of the cylinders and each provided with separate ports to the respective pump 40 cylinders, and the bypass-valve housing provided also with separate ports to the respective working cylinders, and cylindrical rotary valves in said housings each having a central chamber and openings therefrom adapted to 45 register at determined intervals with the ports to the respective cylinders.
5. In a two-cycle internal combustion engine, a pair of working-and-pump cylinders each provided with a valve-controlled inlet 50 to the pump portion thereof on one side of the cylinders, a cylindrical valve housing on the opposite side of said cylinders having separate openings communicating with the working and pump portions of each cylinder, and a rotary cylindrical valve in said 55 housing having a central reservoir chamber and ports controlling communication between the latter and the respective working and pump cylinders.
- 60 6. In a two-cycle internal combustion en-
- gine, a pair of working-and-pump cylinders having valved inlets to the pump portions thereof on one side of the cylinders, a cylindrical bypass-valve housing on the opposite side of said cylinders having independent ports and passageways to the respective working and pump portions of each cylinder, a cylindrical rotary valve in said housing forming a central reservoir chamber and provided with openings adapted to 65 register at determined intervals with the ports to the respective cylinders.
7. In a two-cycle internal combustion engine, a pair of working-and-pump cylinders having separate intake-valve and bypass-valve housings each provided with separate ports to the respective pump cylinders and the bypass-valve housing provided also with separate ports to the respective working cylinders, and valves in said housings arranged 70 to coöperatively control the several ports; the heads of said working cylinders being provided with exhaust openings having exhaust valves, and said valves being positively actuated in accord with said reservoir 75 valves.
8. In a two-cycle internal combustion engine, a pair of working-and-pump cylinders having separate cylindrical intake-valve and bypass-valve housings arranged on opposite sides of the cylinders and provided with ports to the several cylinders, and communicating water jackets for said working 80 cylinders and valve housings.
9. In a two-cycle internal combustion engine, a pair of working-and-pump cylinders having separate cylindrical intake-valve and bypass-valve housings oppositely arranged in line with the junctions of the working and pump portion of said cylinder 90 and provided with ports to the several cylinders, and communicating water jackets for said working cylinders and valve housings.
10. In a two-cycle internal combustion engine, a pair of working-and-pump cylinders having separate cylindrical intake-valve and bypass-valve housings each provided with separate ports to the respective pump cylinders, and the bypass-valve housing provided also with separate ports to the respective 100 working cylinders, and hollow rotary valves in said housings arranged to coöperatively control the several ports, said intake valve being rotated at half the speed of said bypass valve.

In testimony whereof we affix our signatures.

ROBERT F. LONABERGER.
CALVIN R. BALMER.
